PRINTING PRESS

William Ward Davidson, Evanston, and Edward F. Dell, Park Ridge, Ill.; said Dell assignor to Davidson Manufacturing Corporation, Chicago, Ill., a corporation of Illinois

Application May 24, 1941, Serial No. 395,078

12 Claims.

(Cl. 101—144)

The two-cylinder two-purpose printing presses recently placed on the market by the Davidson Manufacturing Corporation under the trademark "Dual Duplicator" have been received with exceptional favor, but it is nevertheless desirable to provide a press of this general nature which can be sold in a lower price class, which will do a satisfactory printing job and which will be reasonably convenient to use, even though it does not have all the advantages of the press which has been so favorably received. An important object of the present invention, therefore, is to provide a cheaper press which will print satisfactorily and conveniently either by direct letter-press printing, by which is meant printing from raised inked surfaces such as type, or offset planographic printing, by which is meant printing from a smooth planographic surface onto a transfer blanket and from it onto the sheet to be printed.

One of the features of the invention which is important in respect to economy and convenience is in providing an inexpensive construction in which prints produced by either direct or offset printing can be delivered right-side-up for inspection. According to the present invention, this is accomplished by having the blanket roll above the larger roll which carries both the plate and platen surfaces for offset printing, and using this same upper roll as the type-carrying roll for direct printing. Thus, the printing is always done on the upper surface of the sheet, so that the sheet never needs to be turned over for right-side-up delivery and hence may be ejected to the catcher or collecting box with the utmost simplicity. It will be observed, however, that this requires inking the large lower roll for offset printing and inking the upper roll for direct printing. According to the present invention, this has been accomplished without loss of the desired economy by providing an inking mechanism which may easily be shifted from the lower roll to the upper roll and which will operate in either position with a minimum of connections with the rest of the press. In short, the inking mechanism is made in a substantially complete self-contained unit.

The location of the blanket roll at the top has the advantage of rendering it unusually accessible for cleaning and inspection.

The press utilizes a relatively small number of inking rolls with the result that even when these inking rolls are positioned below the larger lower roll, they do not extend downwardly therefrom far enough to be inconveniently low.

Additional objects and advantages of the invention will be apparent from the following description and from the drawings, in which:

Fig. 1 is a diagrammatic view of the press chosen for illustration of the invention, arranged for offset printing.

Fig. 2 is a somewhat less diagrammatic view on a larger scale, showing details of the dampening and inking units and showing various other controls diagrammatically.

Fig. 2a is a fragmentary view of a different form of platen that may be used in this invention.

Figs. 3 and 4 are views corresponding to Figs. 1 and 2 but showing the press arranged for direct printing.

Fig. 5 is a diagrammatic view illustrating the fact that the axis of the inking roll in Figs. 3 and 4 is in the same position whether the co-operating type roll is in printing engagement with the other printing roll or not.

Fig. 6 is a somewhat diagrammatic plan view of the structure shown in Fig. 4.

Fig. 7 is a view taken approximately on the line 7—7 of Fig. 6.

Fig. 8 is a fragmentary view showing particularly the operation of the ductor roll.

Fig. 9 is a fragmentary detail view taken approximately on the line 9—9 of Fig. 8.

Fig. 10 is a fragmentary detail view taken on the line 10—10 of Fig. 9.

A preferred form of the invention has been chosen for illustration and description, in compliance with section 4888 of the Revised Statutes, but persons skilled in the art will readily perceive other means for accomplishing the same results, and the claims are therefore to be construed as broadly as possible, consistent with the prior art.

GENERAL ORGANIZATION

Before considering the detailed structure of the machine it will be helpful to describe its general organization. Although the press is adapted for both offset lithographic printing and direct letter-press or typographic printing, it will be described first with respect to the offset lithographic printing, the press arrangement for which is diagrammatically illustrated in Fig. 1.

A. *Lithographic offset printing*

The sheet of paper A in Fig. 1 was delivered by any suitable sheet-separating means or by hand to a diagonal tape conveyor board D, by which it was fed against a suitable side guide

for lateral registration and against suitable stop fingers E (Fig. 2) which at the time were vertically positioned. The stop fingers E stop the sheet with its leading end between the feed rollers H, which close upon the sheet and grip it while the sheet is still stationary, and then rotate to move the sheet toward the bite of the printing cylinders, the stop fingers E moving out of the way as the rollers rotate.

During this process of bringing the sheet A to 10 the bite of the cylinders, the lower or larger cylinder or roll I which carries a plate J on one peripheral segment and a platen surface K on another peripheral segment has been rotated to ink up the plate J and apply the image to the blanket L carried on the smaller upper cylinder M, where it is ready to be applied to the sheet when it reaches the bite of the printing cylinders. Cylinder I rotates in a counterclockwise direction, as seen in Fig. 1, so that the plate J is first dampened by the dampening unit N so that when it reaches the inking unit O, the ink will stick only to the image portion of the plate. Between the printing of successive sheets the plate J rotates in contact with the blanket L and applies its lithographic image to the blanket L. On the next half revolution of the large drum or cylinder I the gripper Q receives and grips the leading edge of the sheet A and carries it through the bite between the blanket L and the platen segment K so that the blanket prints the image on the upper face of the sheet. In feeding the sheet to the gripper Q, the feed rollers H feed it slightly faster than the peripheral speed of the printing cylinders to press it into registration against stop fingers associated with the gripper Q. The gripper Q releases the sheet in time for it to pass into catcher or collecting box P.

A suitable cam is provided along each margin of the platen segment K to lift the dampening form roller and the inking form roller from the platen when it passes beneath these rollers. It should be noted that during the entire cycle of the printing cylinder I the printing rollers are continuously rotating to break up the ink and replenish the ink on the ink form roller for the next application of ink to the printing plate.

B. Direct letter-press printing

For direct printing, the press is changed as shown in Fig. 3. A type-bearing member U is substituted for the blanket L on the blanket cylinder M, and the inking unit O is moved to the upper left-hand corner of the press, as seen in Fig. 3, so that its form roller will engage the type face on the typographic member U. The typographic member U may conveniently comprise a rubber plate, the maximum effective thickness of which is the same as that of the blanket. According to present commercial practice, this is $\frac{9}{1000}$ of an inch. If the platen is suitable for use with a metal plate, as indicated in Fig. 2a, the plate may be of metal instead of rubber. The plate J of Fig. 1 will be removed and the form-dampening roll will be shifted to an inactive position. It will now be observed that the upper roll M will continue to print on the upper face of the sheet A' which is carried by the platen K as before. The sheet will be delivered to the same collecting box or catcher P as in Fig. 1 and still will be delivered printed-side-up.

FEEDING APPARATUS

The feeding apparatus may be substantially the same as that illustrated in copending application 75

Serial No. 164,546, the disclosure of which is hereby made a part hereof by reference. As diagrammatically indicated in Fig. 2, the upper feed roller H is raised and lowered by a cam 11, and, after it has been lowered to press a sheet against the lower feed roller H, this roller is started smoothly by a rack 12 controlled by cam 13. With the present press, the provision of the gripper Q has proved convenient and hence the cam 13 will be shaped to over-feed the sheet A somewhat so as to buckle it slightly against the registration stop fingers 14 associated with the gripper Q. The gripper Q is opened by cam 16 to receive the sheet and is closed on the sheet before the sheet leaves the feed rollers H.

EJECTING MECHANISM

The gripper Q continues to grip the sheet until the leading end has passed under an ejector roller 18. While plate J is passing under ejector roller 18, the ejector roller is held away from the plate by cam 19. After the leading edge of the sheet passes under the ejector roller 18, the spring-urged roller 18 is lowered onto the sheet by cam 19 and the gripper Q opens wide enough to allow the leading edge of the sheet to escape therefrom. The leading edge of the sheet flies out to engage the outer side of the stripper 21 so that the stripper 21 and the ejector roller 18 reliably remove the sheet from the press and deliver it to the catcher or collecting box P.

DAMPENING UNIT

In lithographic printing, the plate J must be dampened before it is inked. The image on the plate is a greasy image and the dampening water therefore will not stick to the image portion of the plate but it does wet the remainder of the plate. The ink then will not stick to the wet portion of the plate, and so only the image portion of the plate is inked.

Dampening units conventionally include a fountain or pan 26 for the dampening liquid (which is mostly water), a fountain roll 27, a ductor roll 28, a distributor roll 29, and dampening form roller 30. Also, in accordance with conventional practice, the proper amount of dampening liquid is fed to the distributor roll 29, the dampening form roller 30, and by it to the plate by having the ductor roll shift from engagement with roll 29 to the position shown in Fig. 2 in engagement with the fountain roll 27 and remain in contact therewith for the predetermined angular movement of the fountain roll 27, after which the ductor roll 28 shifts back into engagement with the distributor roll 29, in which position it passes the dampening liquid on to that roll, which passes it to the form roller 30.

According to the present invention, the operation of these various rolls is very simple. The dampening form roller 30, distributor roll 29, and ductor roll 28 when in contact with the distributor roll 29 are all driven by the contact of the roller 30 with the plate J. The ductor roll 28 is shifted by a cam 31 in Fig. 4, which actuates a cam follower 32 on a lever 33 rigid with shaft 34 on which are rigidly mounted the ductor roll supporting arms 36. The cam 31 is driven by a sprocket 37 and chain 38 from a sprocket 39 rotating rigidly with the larger cylinder I. Sprockets 37 and 39 have the same number of teeth so that cam 31 rotates synchronously with cylinder I. It is thus seen that the ductor roll 28 is shifted against the fountain roll 27 once during each revolution of the cylinder I.

The fountain roll 27 is also actuated by the chain 38 so that this chain is the only special driving connection required between the dampening unit N and the rest of the press. A ratchet 41 is mounted in rigid relationship to the fountain roll 27 and is actuated by a pawl 42 carried by a lever 43 pivoted concentrically with the ratchet 41 and actuated by a link 44 from crank disc 45 which is driven jointly with cam 31 by the sprocket 31. According to conventional practice, an adjustable slide may be interposed between pawl 42 and ratchet 41 to vary the portion of the stroke of the pawl 42 during which it is free to engage the ratchet 41. This will determine the angular movement of the fountain roll 27 during each cycle of the press.

Some of the dampening rolls, preferably rolls 28 and 30, are coated with a conventional absorbent covering, and pinion 46 meshes with gears on the cylinder I and on distributor roller 29 to drive the dampening roller even when form roller 30 is not in contact with the plate, thus assuring an even distribution of the dampening liquid.

The fountain 26 is preferably made of porcelain, as this will avoid any electrolytic action between it and the dampening liquid.

INKING UNIT

The inking unit conventionally includes an ink fountain roll 51, an ink ductor roll 52, one or more distributor rolls 53, and one or more form inking rollers 54. In this instance, it is preferred that a single distributor roll and single form inking roller be used, both in the interests of economy and in the interests of keeping the inking unit compact so that adjustments conventionally provided for the ink fountain will be handily located.

Because the inking unit O is shifted from the position shown in Fig. 2 to the position shown in Fig. 4, it is desirable that its actuation be as simple as possible. According to the present invention, it is only necessary to change one link when it is moved. In the position shown in Fig. 2, the link 56 is used, while in the position shown in Fig. 4 the link 57 is used. In both instances the link connects a crank disc 45 with the pivoted plate or lever 58 which carries the pawl 59. The pawl 59 engages the ratchet 61 on the ink fountain roll 51. Thus, for each cycle of the press the ink fountain roll 51 is rotated through an angular distance corresponding to a certain number of teeth on the ratchet 61. According to conventional practice, this number of teeth is variable by an adjustable slide, not shown, which holds the pawl 59 out of engagement with the teeth of ratchet 61 during any desired part of the movement of the pawl 59.

According to the present invention, the shifting of the ductor roll 52 is effected through the same link 56 or, in Fig. 4, 57. The manner in which this is accomplished is best seen by reference to Figs. 8 and 9. A rack bar 66 is pivoted to the pawl-carrying plate 58 and drives a pinion 67 in opposite directions, the rack being held in engagement with the pinion by rollers 68 on pivoted plate 69 (Fig. 9).

With the parts starting in the position shown in Fig. 8, the pinion 67 will rotate counterclockwise upon movement of the rack 66 to the right. This counterclockwise movement of the pinion 67, however, is an idle movement and no movement is transmitted by it. During this movement the pawl 59 drives the ink fountain roll 51.

For the sake of uniformity it is desirable that the ductor roll 52 remain in contact with the fountain roll 51 during the entire movement of the fountain roll. During this movement, and in fact during the entire first stroke of rack 66 from the Fig. 8 position, the ductor roll 52 is held in contact with the fountain roll 51 by virtue of a spring 71, seen in Fig. 4.

In the return stroke of rack 66, during which 10 the ink fountain roll 51 is idle, the ductor roll 52 must be moved against the distributor roll 53, held against it for a substantial time, and returned to the ink fountain roll 51. This is accomplished by one revolution of a cam 72 against 15 which cam follower 73 is held by spring 71. The cam 72 is given this one revolution rotation by pinion 67, which is now rotating clockwise as seen in Fig. 8 and which in this direction of rotation drives cam 72 through dog 74. Dog 74 is carried by a collar 76 on the hub of which the cam 72 is rigidly mounted. The dog 74 engages a notch in disc 77 rigid with pinion 67. Preferably there is only one notch in the disc 77 so that it will always turn the dog 74 and the cam 72 to the same position. The notch is, of course, ratchet-shaped so that it will drive the dog only in one direction. The dog 74 may either be urged inwardly by a spring or it may come to rest above the disc 77 each time so that it will fall into the notch by gravity, being held therein during driving by the shape of the notch. The movement of the rack 66 is enough to give the pinion 67 one complete revolution or slightly more with each stroke of the rack 66.

30 It is desirable that the inking distributor and form rollers rotate all of the time whether in contact with the plate or not, and accordingly a gear 78 is provided for the Fig. 2 position of the inking mechanism and a gear 79 for the Fig. 4 position. Each of these gears meshes with a gear driven with the printing surface being inked and also a gear in rigid relationship with one of the inking rolls. Thus, as seen in Figs. 4 and 6, the gear 79 meshes with gear 81, which is the drive gear for cylinder M, and with gear 82 rigid with ink distributor roll 53. The size of the gear 82 is, of course, such as to give the form inking roller 54 the same peripheral speed as the surface being inked.

40 50 It will be observed that as the inking unit is shifted from one position to another, the gear 82 automatically comes into engagement with either the gear 78 or the gear 79 so that no attention need be given to making this driving connection.

55 Best distribution of the ink can only be obtained if the roll 53 slides axially slightly with respect to the roll 51. According to the present invention this is accomplished without any additional driving connection for the inking unit. The same pawl-bearing plate 58 that drives the fountain roll 51 and the rack 66 also reciprocates a link 86 connected to a crank arm 87 which is keyed to shaft 88. Roll 53 and gear 82 rigid with the roll 53 rotate freely on the shaft 88. As seen at the right in Fig. 7 and near the bottom in Fig. 6, the shaft 88 carries a roller 89 which is pivoted to the shaft 88 with an axis which is radial with respect to the shaft 88. The roller 89 rides in a cam slot 91 in a sleeve 92. The sleeve 92 is 60 65 slideable on shaft 88 but is prevented from rotating thereon by a vane 93 projecting into a slot in the sleeve 92, as seen best in Fig. 7. The vane 93 is rigidly mounted on the press frame, or on the bearing for shaft 88 carried by the frame.

70 75 As the shaft 88 is rocked back and forth by the

link 86 and crank arm 87, the roller 89 moves from one end of the slot 91 to the other, and, since it and the shaft are confined against axial movement, the sleeve 92 must move back and forth axially. The sleeve 92 is grooved and forms a bearing for the hub of roll 53 at the adjacent end thereof so that, as the sleeve 92 oscillates back and forth, it also oscillates the roll 53 back and forth along the shaft 88, thus giving the roll 53 the desired sliding movement. On account of this oscillating sliding movement, the roll 53 is often called the vibrator roll.

The form roller 54 is carried by a shaft 96 which is mounted in hubs 97 of pivoted hangers 98 rotatable on the shaft 88. Springs 99 urge the hangers 98 in a direction to press the roller 54 against the surface to be inked. While the platen surface K is passing under the ink roller 54, as seen in Fig. 2, the ink roller 54 is held out of contact with the platen surface K by cam surfaces 101 at the margins of the platen surface K and follower rollers 102 on shaft 96. It may be noted that the dampening form roller 30 is similarly mounted and similarly held off of the platen surface K.

There are, of course, times when it is desirable to hold the inking and dampening rollers 30 and 54 off of the surfaces which they normally engage. This is accomplished by means of cams 103 and 104 which are normally stationary but each of which may be operated by a handle, as the handle 105 in Fig. 7. The cam 103 is so shaped that in different positions it will hold either or both of its associated rollers 30 and 54 out of the active position or will let either or both assume its active position. Screws 106 may be provided for regulating the pressure of the respective rollers 30 and 54 on the surface being inked, or the strength of the springs urging them into contact may be predetermined to provide this pressure. To avoid disturbing the adjustment of the inking pressure control screw 106 when the inking unit is shifted from the Fig. 2 position to the Fig. 4 position, cam 104 may be provided with means to adjust the angular position to which it may be returned after moving it to its throw-out position.

SHIFTING OF THE INKING UNIT

In order to shift the inking unit O from the position shown in Fig. 2 to the position shown in Fig. 4, it is merely necessary to remove the link 56, loosen the securing bolts 111, slide the whole unit out of the frame and slide it into the frame at the new position, and apply the link 57. Since the ink unit is at the right of the press, as seen in Fig. 2, and at the left when in the new position shown in Fig. 4, it has in effect been pivoted 180° about a vertical axis so that, although the cylinder M rotates in the direction opposite to the direction of cylinder I, the movement of the parts will automatically be correct for both cylinders. It will be observed, however, that the link 56 is on the near side of the press while the link 57 is on the far side of the press. This necessitates the provision of two discs 45 on opposite sides of the press, both discs being rigid with respect to the same shaft so that they may both be driven by the single chain 38.

It will be understood that the ink fountain is provided with the conventional series of screws for adjusting the distribution of ink feed along the length of fountain roll 51.

It will also be observed that the arrangement of the inking rolls is different in the Fig. 4 posi-

tion from that shown in the Fig. 2 position. This is permitted by the mounting of the roller 54 and it will be observed that in each instance the roller 54 is urged in the proper direction against the surface being inked in spite of the changed relationship between the inking unit and its cooperating cylinder. The changed arrangement of rolls provides maximum visibility of the collection box in the Fig. 4 position and maximum accessibility of the ink fountain in the Fig. 2 position where accessibility presents a problem. Although the spring 89 is under greater tension in Fig. 4 than in Fig. 2, this does not affect the inking pressure since this pressure is determined by the adjustment of screw 106.

THROW-OUT

It is, of course, desirable that at times the cylinders I and M be separated so that, when the press is rotating without sheets being fed, the cylinder M will not print onto the cylinder I. In the present invention this is accomplished by journaling the cylinder M on an eccentrically journaled shaft 116 which, as seen in Fig. 4, is urged in a cylinder-separating direction by a spring 117, may be moved in the opposite direction by the handle 118, and is latched in the printing position by arm 119 and latch 120. Latch 120 is in turn provided with a handle 121 for releasing the latch to cause a throw-out movement of shaft 116 under influence of the spring 117.

An important point to be noticed is seen best in Fig. 5, from which it will be observed that in the two positions of the cylinder M the distance between its axis and the axis of the roller 54 is the same. The position of the axis of the roller 54 is, of course, determined by the cam 104 and screw 106.

By virtue of having the distance between these axes the same in both positions of the cylinder M, the inking pressure will be the same in both positions so that the cylinder M may be properly inked up while it is rotating in the throw-out position.

It is desirable that the doctor roll 52 shift against the vibrator roll 53 at the earliest moment in the cycle of the press which will not result in this freshly applied ink being carried to the plate or type without being first broken up. Due to the differing positions of the parts, this earliest possible moment does not occur at the same time in the Fig. 4 arrangement as in the Fig. 2 arrangement. However, the driving of the pivoted plate 58 from different crank discs 45 in the two instances makes it possible to provide exactly the correct timing in both instances. This is accomplished merely by setting each of the crank discs 45 with its pin in the proper position to actuate the plate 58 at the right time for the parts, considering the dimensions of the parts and their relative positions. No attempt has been made to select this positioning for the crank discs 45 in the drawings since the correct positioning is most easily determined with an actual machine. In brief, the discs 45 should be set in such position that after the doctor roll 52 applies fresh ink to the roll 53, this ink will be carried around the roll 53, passed in part to the roll 54, and carried around the roll 54 to reach the position of the bite of the roll 54 with the plate J just after the plate J passes out of contact with the roll 54. This gives the maximum time during which rotation of the rolls 52, 53 and 54 will break up and distribute the ink before fresh ink can be applied to the plate. As previously indicated, the

independent initial setting of the two crank discs 45 makes possible this accurate setting of the ink unit timing independently for the two positions of the ink unit.

Under some circumstances it is not necessary to move the ink unit at all in order to print by direct printing from rubber type on the cylinder M. Such printing can be accomplished, by the use of the invention of Davidson copending application Serial No. 347,454, by replacing the plate J with an unetched plate and using this plate as the form roller for the rubber type on cylinder M. The cam 103 is turned to a position to keep the dampening unit out of contact with the plate, and the roller 64 applies ink over the entire surface of the plate. This ink is in turn applied to the raised surfaces of the rubber type plate which prints on the upper face of the sheet.

The shifting of the ink unit is particularly important when a metal type plate is to be used on cylinder M because such plate probably cannot be satisfactorily inked by a metal inking roller such as would be formed by the unetched plate in place of the plate J.

Printing with a metal plate on the solid metal platen segment K is likely not to be very satisfactory. Accordingly, it will usually be preferred to provide a platen of the general type illustrated in Fig. 2a, in which the main part 126 of the platen segment is of slightly smaller radius than that shown in the other figures and an overlay 127 is used to provide the proper surface characteristics and to build the platen out to the proper radius. The overlay may comprise any conventional tympan, or brass sheet of $10/1000$ to $20/1000$ of an inch thickness with suitable underlays or a tough rubber blanket made of a blanket which is somewhat harder than conventional lithographic blankets so that the type will not mar the sheets by pressing into the blanket excessively. In some instances the brass sheet with its underlays will be preferred because the underlays may be removed in accordance with the thickness of the sheet to be run. This will avoid printing imperfections due to improper radius and also avoid the necessity for any ready adjustability of the cylinders to provide for maintaining the right printing pressure with different thicknesses of sheet. If such adjustability is provided, however, the relatively hard rubber blanket may be preferred since the proper hardness of platen blanket will be entirely satisfactory to serve both as a lithographic platen and as a letter-press platen, whether the raised letter-press image be formed of rubber or metal. If a brass sheet is preferred for the lithographic printing, it may be replaced by the blanket. Since the blanket will be thicker than the brass sheet, it will probably be necessary to remove some underlay with the brass sheet. It will be observed that with either of these arrangements the cylinders themselves need never be changed but it will only be necessary at most to remove or change the surface members on the plate, blanket roll and platen. In fact, it will not even be necessary to change the platen surface, at least if the relatively hard rubber blanket is used for this surface all the time. By moving the inking unit, the proper ink form roller for metal is provided at the proper place so that for satisfactory printing it is only necessary to have a proper platen surface.

From the foregoing it is seen that a press has been provided in which the upper side of the sheet is printed either with offset lithographic

printing or direct letter-press printing, optionally. Furthermore, the press is exceptionally inexpensive to manufacture for a high quality, two-purpose press since it is not necessary to provide any means for turning over the sheet with either method of printing nor is it necessary to provide any extra inking unit for either method of printing, the single inking unit being interchangeable between two positions for the two methods of printing. All of the essentials to high quality printing have been retained.

We claim:

1. A printing press for printing the upper face of a sheet optionally by a raised image method or an offset lithographic method including a smaller upper cylinder and a larger lower cylinder having a platen segment and a plate segment thereon adapted to receive a plate, dampening means for the plate, an inking unit for the plate adapted to apply paste ink thereto and having a plate-engaging roll and including a fountain roll, a second roll and a ductor roll shiftable between the fountain roll and the second roll, and means actuated by a single lever for driving the fountain roll intermittently and shifting the ductor roll in synchronism therewith; said upper cylinder being adapted to have a transfer surface thereon for receiving an image from the plate and transferring it to the upper face of a sheet on the platen, and being adapted alternatively to have a direct printing member thereon with a raised image adapted to print the upper face of a sheet on said platen with paste ink, and means for detachably mounting the inking unit alternatively at two positions to cause the plate-engaging roll thereof to engage the direct printing member on the smaller cylinder or, alternatively, the surface of the plate.
2. A printing press for printing the upper face of a sheet optionally by a raised image method or an offset lithographic method including a smaller upper cylinder and a larger lower cylinder having a platen segment and a plate-bearing segment thereon, dampening means for the plate, and inking means for the plate comprising a plurality of ink rollers one of which rotates in contact with the plate, said upper cylinder being adapted to have a transfer surface thereon for receiving an image from the plate and transferring it to the upper face of a sheet on the platen, and being adapted alternatively to have a direct raised image printing member thereon to print the upper face of a sheet on said platen, and means for detachably mounting the inking unit alternatively at two positions to cause the plate-engaging roller thereof to engage the direct printing member on the smaller cylinder or, alternatively, the surface of the plate; said inking unit being adapted to cooperate with either size of cylinder and in each position being adapted to apply a paste type of ink.
3. A printing press for printing the upper face of a sheet optionally by a raised image method or an offset lithographic method including a smaller upper cylinder and a larger lower cylinder having a platen segment and a plate-bearing segment thereon, dampening means for the plate, and inking means for the plate comprising a plurality of ink rollers one of which rotates in contact with the plate, said upper cylinder being adapted to have a transfer surface thereon for receiving an image from the plate and transferring it to the upper face of a sheet on the platen, and being adapted alternatively to have a direct printing member thereon with

a raised image adapted to print the upper face of a sheet on said platen, and means for detachably mounting the inking unit alternatively at two positions to cause the plate-engaging roller thereof to engage the direct printing member on the smaller cylinder or, alternatively, the surface of the plate; said inking unit being adapted to cooperate with either size of cylinder and in each position being adapted to apply a paste type of ink.

4. A lithographic press including a plate, a transfer medium, and a platen, mounted on cylinders with bites formed by the plate and the transfer medium and by the transfer medium and the platen, dampening and inking means for the plate comprising a dampening fountain roll, an ink fountain roll, dampening distributor and form rollers, ink distributor and form rollers, a dampening ductor roll, an ink ductor roll, a member driven in synchronism with one of the cylinders, linkage driven uniformly by said member connecting said member to rotate the fountain rolls during a part of the cycle, and means for operating the ductor rolls to position them alternately on the fountain rolls and on the distributor rolls, the means for operating the ink ductor roll being actuated by said linkage and shifting the ink ductor roll only while the ink fountain roll is stationary.

5. A printing press including a smaller upper cylinder and a larger lower cylinder having a platen segment and a plate-bearing segment thereon, dampening means for the plate, and inking means for the plate comprising a plurality of ink rollers one of which rotates in contact with the plate, said upper cylinder being adapted to have a transfer surface thereon for receiving an image from the plate and transferring it to the upper face of a sheet on the platen, and being adapted alternatively to have a direct printing member thereon to print the upper face of a sheet on said platen, and means for detachably mounting the inking unit alternatively at two positions one below the center of the lower cylinder and the other above the center of the upper cylinder, and said inking unit having its plate-engaging roller resiliently urged in a given direction but shiftable through a wide angle so as to be urged toward the cooperating cylinder in each position of the inking means with the remainder of the inking means positioned with the same side up in both positions of the inking means.

6. A printing press for printing the upper face of a sheet optionally by a raised image method or an offset lithographic method including a printing couple comprising a smaller upper cylinder and a larger lower cylinder, the larger cylinder having a platen surface and a plate surface, and the upper cylinder being adapted to have a transfer surface and receiving the image from the plate and printing it on the upper face of the sheet against the platen, and being adapted alternatively to have a raised image surface thereon an inking unit means for detachably mounting the inking unit alternatively at two positions to engage alternatively the plate surface of the lower cylinder or the raised image surface of the upper cylinder; said inking unit being adapted to cooperate with either size of cylinder and in each position being adapted to apply a paste type of ink.

7. A printing press having thereon two cylinders either of which may bear an image surface to be inked, an inking unit means for detachably mounting the inking unit alternatively at two

positions in one of which it inks the image surface on one cylinder and in the other of which it inks the image surface on the other cylinder, and means for driving said inking unit including a shaft driven in synchronism with one of the cylinders, crank members on opposite ends of the shaft adjacent opposite sides of the press, and link means adapted to cooperate with one of the crank members for one position of the inking unit and with the other crank member for the other position of the inking unit, the inking unit in being moved from one position to the other, being turned end for end so that attachment of the link means is made to the crank member on the opposite side of the press.

8. A printing press having thereon two cylinders either of which may bear an image surface to be inked, an inking unit, means for detachably mounting the inking unit alternatively at two positions in one of which it inks the image surface on one cylinder and in the other of which it inks the image surface on the other cylinder, and means for driving said inking unit consisting, except for parts moved with the inking unit, solely in gears automatically meshed in each position as the inking unit is moved into position, and link means for a single connection with its driving mechanism comprising a shaft driven in synchronism with one of the cylinders, crank members on opposite ends of the shaft adjacent opposite sides of the press, the link means being adapted to cooperate with one of the crank members for one position of the inking unit and with the other crank member for the other position of the inking unit, the inking unit in being moved from one position to the other, being turned end for end so that attachment of the link means is made to the crank member on the opposite side of the press.

9. A printing press including a smaller upper cylinder and a large lower cylinder having a platen segment and a plate segment thereon adapted to receive a plate, dampening means for the plate, an inking unit for the plate having a plate-engaging roll and including a fountain roll, a second roll and a ductor roll shiftable between the fountain roll and the second roll, and means actuated by a single lever for driving the fountain roll intermittently and shifting the ductor roll only while the fountain roll is stationary; said upper cylinder being adapted to have a transfer surface thereon for receiving an image from the plate and transferring it to the upper face of a sheet on the platen, and being adapted alternatively to have a direct printing member thereon with a raised image adapted to print the upper face of a sheet on said platen, and means for detachably mounting the inking unit alternatively at two positions to cause the plate-engaging roll thereof to engage the direct printing member on the smaller cylinder or, alternatively, the surface of the plate.

10. A printing press having thereon two cylinders either of which may bear an image surface to be inked, an inking unit, means for detachably mounting the inking unit alternatively at two positions in one of which it inks the image surface on one cylinder and in the other of which it inks the image surface on the other cylinder, and means for driving said inking unit consisting of drive means driven with the press and stationarily located, and drive parts movable with the inking unit as it is shifted including gear means automatically meshing in each position as the inking unit is moved into position, and link

means for a single connection in each position with the drive means, said gear means and said link means being the sole driving connections for the inking unit.

11. A printing press having thereon two cylinders either of which may bear an image surface to be inked, an inking unit, means for detachably mounting the inking unit alternatively at two positions in one of which it inks the image surface on one cylinder and in the other of which it inks the image surface on the other cylinder, and means for driving said inking unit in either position; said inking unit being positioned substantially above the bottom of the cylinder in one position and in the other position being positioned generally close to the bottom of the cylinder, and said inking unit including a distributor roll and a form roller shiftable angularly about the distributor roll to bear generally upwardly against the surface being inked in the last-named position and to bear more horizon-

20 tally against the surface being inked in the other position.

12. A printing press having thereon two cylinders either of which may bear an image surface to be inked, an inking unit, means for detachably mounting the inking unit alternatively at two positions in one of which it inks the image surface on one cylinder and in the other of which it inks the image surface on the other cylinder, 10 and means for driving said inking unit in either position; said inking unit being positioned higher angularly about the axis of the cooperating cylinder in one position than in the other, and said inking unit including a distributor roll and a form roller shiftable angularly about the distributor roll to bear at one angle against the surface being inked in the last-named position and to bear at another angle against the surface being inked in the other position.

WILLIAM WARD DAVIDSON.
